(57) **CLAIM**

The ornamental design for a boiler control-panel with a lid, as shown and described.

DESCRIPTION

1.1 is a front view of a boiler control-panel with a lid;
1.2 is a right-side view thereof;
1.3 is a left-side view thereof;
1.4 is a rear view thereof;
1.5 is a top view thereof;
1.6 is a bottom view thereof;
1.7 is a perspective view thereof in a closed position;
1.8 is a perspective view thereof in an open and extracted position;
1.9 is a perspective view thereof in an open and retracted position;
1.10 is a perspective view thereof of an enlarged portion of FIG. 1.7;
1.11 is a perspective view thereof of an enlarged portion of FIG. 1.8;
1.12 is a perspective view thereof of an enlarged portion of FIG. 1.9.
Parts shown by broken lines are not part of the design.
